STARTING MEANS FOR INTERNAL
COMBUSTION ENGINES

Charles Horace Lionel Wynne, Henry Christopher Tryon, and Frank Raymond Faber Ramsay, London, England, assignors to D. Napier & Son Limited, London, England, a company of Great Britain

Application June 26, 1941, Serial No. 399,914
In Great Britain June 18, 1940

14 Claims. (Cl. 123—187.5)

This invention relates to starting means for internal combustion engines, more especially the engines of aircraft, and by means of apparatus of the combustion, inertia or other non-continuously turning type. When a starter of this type is employed the engine cylinders are liable to become overcharged with fuel unless a measured quantity of priming fuel is delivered into the cylinders at each starting attempt. The object of the invention is to provide for the delivery into each cylinder of a suitable quantity of the priming fuel while the starter is causing the engine to be turned over, such fuel delivery being under a pressure which will cause the fuel to enter the cylinder in a finely atomized state so that it will be there maintained in a state of suspension while producing in the cylinder the desirable degree of turbulence.

The starting apparatus of the above mentioned type with which the invention is intended to be more particularly associated comprises known means for turning over the engine by power derived from gas pressure resulting from the combustion of a charge contained in a cartridge which is ignited or fired when an electric circuit is completed. The invention is applicable, however, for use with other known starting apparatus of the general type in question which can be brought into operation by means actuated electrically, hydraulically or pneumatically.

According to this invention there is combined with a starting apparatus of the type indicated above, a device which will cause a measured quantity of priming fuel to be injected into the engine cylinder and means for bringing this device into operation and for causing the starter to function as the fuel charge is entering the engine cylinder. The device comprises a chamber, which may conveniently be formed as a cylinder, adapted to contain under pressure the amount of fuel required for a priming charge and means for permitting the fuel to pass from this chamber into the engine cylinder and for simultaneously bringing the starter into operation. Means are provided for varying the capacity of this chamber in which the fuel is maintained under pressure so that the chamber will contain and determine the amount of fuel required for a priming charge. The fuel flow from this chamber is controlled by a valve and the means by which this valve is actuated will also cause the starter to function. Where as is preferred the starting apparatus is caused to function by the closing of an electric circuit, the electric current for example firing a cartridge which generates the required

site gaseous power, the closing of this circuit is effected while the priming charge of fuel is being injected into the engine cylinder.

With the fuel-containing chamber formed as a cylinder, as is preferred, there is in this cylinder a piston which is movable in the cylinder through a variable distance from the delivery end of the cylinder and the distance through which the piston is permitted to move when fuel is being delivered into the chamber determines the capacity of the chamber in accordance with the desired amount of fuel which is to be in the priming charge. The fuel in this chamber is kept under pressure by means of a spring or air pressure acting on the piston and a non-return valve controls the flow of fuel from the chamber to the engine cylinder. When this valve is lifted to allow the fuel to pass to the engine cylinder, at the same time there is closed the electric circuit which causes the starter to function. It is convenient to arrange in this electric circuit two separate contacts which have to be made simultaneously so as to effect the closing of the circuit. One of these contacts is made when the non-return valve is lifted and the other contact is made when the piston as it moves under the pressure exerted on it is approaching the end of the fuel cylinder and delivery of the priming charge is about to end.

The accompanying drawings illustrate by way of example alternative constructions and an arrangement of the apparatus which may be employed in carrying the invention into practice. In these drawings,

Figure 1 is a sectional elevation of one form of the fuel-containing chamber and the parts more particularly associated with it.

Figure 2 is a similar view of the cylindrical chamber showing an alternative arrangement for maintaining in the chamber the necessary pressure on the fuel therein certain working parts being broken away or omitted for the sake of clearness.

Figure 3 shows diagrammatically how the invention may be arranged in relation to an engine.

Referring to Figure 1 the fuel-containing chamber is here constituted by the cylinder A, in one end B which may be integral with the cylinder, are the passages through which the fuel enters and flows away from the chamber. The other end C of the cylinder is adjustable being provided with a sleeve C' externally screw-threaded to engage an internal thread extending along in the end portion of the cylinder A. Within the latter lies and can move a piston D having a rod D' which extends and can move freely

through a central opening C^2 in the cylinder head C. In the cylinder and between the head C and the piston D is a spring E which tends constantly to move the piston towards the end B of the cylinder. By adjustment of the cylinder head C the end of whose sleeve C^1 forms an abutment, the distance through which the piston can move in the cylinder against the spring can be varied and thus the capacity of the cylinder may be changed to measure and determine the amount of fuel which the cylinder can hold at one time as a priming charge.

By way of the passage F in the end B of the cylinder A fuel may be delivered past the non-return valve F^1 by a pump operated by hand or otherwise when required. The outlet passage G leads from the fuel cylinder to the engine cylinder and the flow through this passage is controlled by a non-return valve H. This valve is provided with a spindle H^1 and acted on by a spring H^2 which tends to keep the valve on its seat. In contact with the end of this spindle is the end of one arm J of a lever pivoted at J^1 and adapted to be moved through its other arm J^2 . When thus moved the lever will lift the valve H off its seat and allow the measured charge of fuel contained in the cylinder A to flow through the passage G to the engine cylinder. At the same time the arm J^2 of the lever by bearing on the adjustable stud K will bring together the contacts K^1 , K^2 and close the part of the electric circuit through wires L, L^1 . These contacts will thus be maintained closed so long as the lever is acted on to keep the valve H lifted and allow the flow of fuel to continue from the cylinder A. This electric circuit controls the operation of the starting apparatus R (Fig. 3), but the circuit will not be fully closed until other contacts K^3 , K^4 have been made, and this is effected as the piston D is finishing its stroke when forcing the fuel from the cylinder A into the power cylinders of the engine. On the outer and screwthreaded end portion of the piston rod D^1 is adjustably mounted a sleeve or like member D^2 , having such dimensions both in length and thickness that during the last part of the movement of the piston towards the end B of the cylinder, this sleeve by coming into and remaining in contact with a projection K^5 on the contact member K^4 , will bring the contacts K^3 , K^4 , together, and so complete the closing of the electric circuit through the wires L^1 and L^2 . This circuit will remain closed, so far as it is controlled by these two pairs of contacts K^1 , K^2 , and K^3 , K^4 , until fuel is again forced into the cylinder A and the piston thereby raised so as to move the sleeve D^2 clear of the contact-making projection K^5 . This will be when the cylinder is once more filled with a priming charge.

In the modified construction of fuel-containing cylinder shown in Figure 2 in place of the necessary pressure being exerted on the piston in the cylinder A by a spring, air under a suitable pressure is admitted to the cylinder behind the piston. This air admission is by way of the passage M in which is an adjustable non-return valve M^1 . As in the construction shown in Figure 1 the capacity of the cylinder may be varied, and thus the amount of the fuel in a priming charge, by screwing out or in the cylinder head C, the end of the sleeve C^1 carried by this head forming an abutment which determines the distance that the piston can move when fuel is forced into the cylinder A to charge it.

Figure 3 shows diagrammatically a general

lay-out of the invention and starting apparatus as it may be arranged in practice. In this drawing the engine N is supplied with fuel for normal running from the fuel tank O through the pipe line O^1 . A branch pipe O^2 leads to a hand pump P by which fuel can be drawn from the pipe O and delivered into the measuring chamber A for the priming charge through the pipe F^2 . The lever J by means of which the fuel delivery valve is lifted and the contacts K^1 , K^2 brought together has its second arm J^2 connected by a link J^3 to one arm Q of a bell-crank lever pivoted at Q^1 , the other arm Q^2 of this lever being connected to an operating knob Q^3 or like device by means of which the lever J J^3 can be actuated.

The starting apparatus is indicated at R and conveniently is of the known type comprising a cartridge of combustible material adapted to be fired by closing an electric circuit when the gaseous pressure produced serves to turn over the engine. The electric circuit includes a battery L^4 and switch S with the wires L , L^1 and L^2 and the contacts K^1 , K^2 , and K^3 , K^4 , the latter not being shown in this view, but being as shown in Figure 1. The circuit may be grounded as at T through the metallic parts of the apparatus. The fuel is delivered from the chamber A to the cylinders of the engine N by way of the piping G^1 .

The switch S enables the circuit controlling the operation of the starter R to be wholly cut out if desired while leaving the priming device free to be actuated as required by means of the knob Q^3 .

What we claim as our invention and desire to secure by Letters Patent is:

1. In apparatus for starting an internal combustion engine the combination of a starter of the non-continuous turning type indicated, a chamber adapted to contain the fuel required for a priming charge for the engine cylinder, means for delivering fuel into this chamber, means for maintaining under pressure the fuel in this chamber, a valve controlling the flow of fuel from this chamber into the engine cylinder, and means for actuating this valve so as to permit such flow and for causing the starter to function as the charge of priming fuel is entering the engine cylinder as set forth.

2. In apparatus for starting an internal combustion engine the combination of a starter of the non-continuous turning type indicated, a chamber adapted to contain the fuel required for a priming charge for the engine cylinder, means for varying the capacity of this chamber and thereby determining the amount of fuel which is to constitute the priming charge, means for delivering fuel into this chamber, means for maintaining under pressure the fuel in this chamber, a valve controlling the flow of fuel from this chamber into the engine cylinder, and means for actuating this valve so as to permit such flow and for causing the starter to function as the charge of priming fuel is entering the engine cylinder as set forth.

3. In apparatus for starting an internal combustion engine the combination of a starter of the type in which power is obtained from gases under pressure produced by combustion of a charge contained in a cartridge, means comprising an electric circuit for effecting the ignition of this combustible charge, a chamber adapted to contain the amount of fuel required for a priming charge for the engine cylinder, means for delivering fuel into this chamber, means for

maintaining under pressure the fuel in this chamber, means for permitting the fuel to pass from this chamber into the engine cylinder and at the same time closing the said electric circuit and thereby causing the starter to function as the charge of priming fuel is entering the engine cylinder as set forth.

4. In apparatus for starting an internal combustion engine the combination of a starter of the type in which power is obtained from gases under pressure produced by combustion of a charge contained in a cartridge, means comprising an electric circuit for effecting the ignition of this combustible charge, a chamber adapted to contain the fuel required for a priming charge for the engine cylinder, means for varying the capacity of this chamber and thereby determining the amount of fuel which is to constitute the priming charge, means for delivering fuel into this chamber, means for maintaining under pressure the fuel in this chamber, means for permitting the fuel to pass from this chamber into the engine cylinder and at the same time closing the said electric circuit and thereby causing the starter to function as the charge of priming fuel is entering the engine cylinder as set forth.

5. In apparatus for starting an internal combustion engine the combination of a starter of the type in which power is obtained from gases under pressure produced by combustion of a charge contained in a cartridge, means comprising an electric circuit for effecting the ignition of this combustible charge, a chamber adapted to contain the fuel required for a priming charge for the engine cylinder, means for delivering fuel into this chamber, means for maintaining under pressure the fuel in this chamber, a valve controlling the flow of fuel from this chamber into the engine cylinder, and means for actuating this valve so as to permit such flow and at the same time closing the said electric circuit and thereby causing the starter to function as the charge of priming fuel is entering the engine cylinder as set forth.

6. In apparatus for starting an internal combustion engine the combination of a starter of the type in which power is obtained from gases under pressure produced by combustion of a charge contained in a cartridge, means comprising an electric circuit for effecting the ignition of this combustible charge, a chamber adapted to contain the fuel required for a priming charge for the engine cylinder, means for varying the capacity of this chamber and thereby determining the amount of fuel which is to constitute the priming charge, means for delivering fuel into this chamber, means for maintaining under pressure the fuel in this chamber, a valve controlling the flow of fuel from this chamber into the engine cylinder, and means for actuating this valve so as to permit such flow and at the same time closing the said electric circuit and thereby causing the starter to function as the charge of priming fuel is entering the engine cylinder as set forth.

7. In apparatus for starting an internal combustion engine the combination of a starter of the non-continuous turning type indicated, a cylindrical chamber adapted to contain the fuel required for a priming charge for the engine cylinder, a piston movable in this cylinder, means for delivering into this cylinder fuel which then fills the space at one side of the piston, means acting and exerting pressure on the other side of the piston and thereby maintaining under

pressure the fuel in the cylinder, a valve which retains the fuel in the cylinder after it has been delivered thereinto, a valve controlling the flow of fuel from the said cylindrical chamber into the engine cylinder, and means for actuating this valve so as to permit such flow and for causing the starter to function as the fuel charge is entering the engine cylinder as set forth.

8. In apparatus for starting an internal combustion engine the combination of a starter of the non-continuous turning type indicated, a cylindrical chamber adapted to contain the fuel required for a priming charge for the engine cylinder, a piston movable in this cylinder, an adjustable stop which determines the distance through which the piston can move in one direction, means for delivering into this cylinder fuel which then fills the space at one side of the piston the amount of the fuel thus contained in the cylinder being determined by the setting of the said stop which limits the piston movement when the fuel is delivered into the cylinder, means acting and exerting pressure on the other side of the piston and thereby maintaining under pressure the fuel in the cylinder, a valve which retains the fuel in the cylinder after it has been delivered thereinto, a valve controlling the flow of fuel from the said cylindrical chamber into the engine cylinder, and means for actuating this valve so as to permit such flow and for causing the starter to function as the charge of priming fuel is entering the engine cylinder as set forth.

9. In apparatus for starting an internal combustion engine the combination of a starter of the non-continuous turning type indicated, a cylindrical chamber adapted to contain the fuel required for a priming charge for the engine cylinder, a piston movable in this cylinder, means for delivering into this cylinder fuel which then fills the space at one side of the piston, a spring acting on the other side of the piston and thereby maintaining under pressure the fuel in the cylinder, means for varying the distance through which the piston can move and thereby determining the amount of fuel which is to constitute the priming charge, a valve which retains the fuel in the cylinder after it has been delivered thereinto, a valve controlling the flow of fuel from the said cylindrical chamber into the engine cylinder, and means for actuating this valve so as to permit such flow and for causing the starter to function as the charge of priming fuel is entering the engine cylinder as set forth.

10. In apparatus for starting an internal combustion engine the combination of a starter of the non-continuous turning type indicated, a cylindrical chamber adapted to contain the fuel required for a priming charge for the engine cylinder, a piston movable in this cylinder, a cylinder head in screw-threaded engagement with the end of the said cylindrical chamber and constituting an adjustable stop which determines the distance through which the piston can move in the direction of the said cylinder head, means for delivering into this cylinder fuel which then fills the space at one side of the piston the amount of the fuel thus contained in the cylinder being determined by the setting of the said stop which limits the piston movement when the fuel is delivered into the cylinder, means acting and exerting pressure on the other side of the piston and thereby maintaining under pressure the fuel in the cylinder, a valve which retains the fuel in the cylinder after it has been delivered thereinto, a valve controlling the flow of fuel from the said

cylindrical chamber into the engine cylinder, and means for actuating this valve so as to permit such flow and for causing the starter to function as the charge of priming fuel is entering the engine cylinder as set forth.

11. In apparatus for starting an internal combustion engine the combination of a starter of the type in which power is obtained from gases under pressure produced by combustion of a charge contained in a cartridge, means comprising an electric circuit for effecting the ignition of this combustible charge, a cylindrical chamber adapted to contain the fuel required for a priming charge for the engine cylinder, a piston movable in this cylinder, means for delivering into this cylinder fuel which then fills the space at one side of the piston, means acting and exerting pressure on the other side of the piston and thereby maintaining under pressure the fuel in the cylinder, a valve which retains the fuel in the cylinder after it has been delivered thereto, a valve controlling the flow of fuel from the said cylindrical chamber into the engine cylinder, and means for actuating this valve so as to permit such flow and at the same time closing the said electric circuit and thereby causing the starter to function as the charge of priming fuel is entering the engine cylinder as set forth.

12. In apparatus for starting an internal combustion engine the combination of a starter of the type in which power is obtained from gases under pressure produced by combustion of a charge contained in a cartridge, means comprising an electric circuit for effecting the ignition of this combustible charge, a cylindrical chamber adapted to contain the fuel required for a priming charge for the engine cylinder, a piston movable in this cylinder, means for delivering into this cylinder fuel which then fills the space at one side of the piston, a spring acting on the other side of the piston and thereby maintaining under pressure the fuel in the cylinder, means for varying the distance through which the piston can move and thereby determining the amount of fuel which is to constitute the priming charge, a valve which retains the fuel in the cylinder after it has been delivered thereto, a valve controlling the flow of fuel from the said cylindrical chamber into the engine cylinder, and means for actuating this valve so as to permit such flow and at the same time closing the said electric circuit and thereby causing the starter to function as the charge of priming fuel is entering the engine cylinder as set forth.

13. In apparatus for starting an internal combustion engine the combination of a starter of the type in which power is obtained from gases under pressure produced by combustion of a charge contained in a cartridge, means comprising

ing an electric circuit for effecting the ignition of this combustible charge, a chamber adapted to contain the required fuel for a priming charge for the engine cylinder, means for varying the capacity of this chamber and thereby determining the amount of fuel which is to constitute the priming charge, means for delivering fuel into this chamber, means for maintaining under pressure the fuel in this chamber, a valve controlling the flow of fuel from this chamber into the engine cylinder, two separate pairs of switch contacts in the said electric circuit the closing of both of these switches being necessary to complete that circuit, means for actuating the said valve which controls the flow of fuel and thereby permitting the priming charge to flow to the engine cylinder, means for closing one of the said switches when this valve is actuated and the fuel flow to the engine begins, and means for closing the second switch and thus completing the electric circuit towards the end of the delivery of the priming charge and thereby causing the starter to function while the priming fuel is entering the engine cylinder as set forth.

14. In apparatus for starting an internal combustion engine the combination of a starter of the type in which power is obtained from gases under pressure produced by combustion of a charge contained in a cartridge, means comprising an electric circuit for effecting the ignition of this combustible charge, a cylindrical chamber adapted to contain the fuel required for the priming charge for the engine cylinder, a piston movable in this cylinder, means for delivering into this cylinder fuel which then fills the space at one side of the piston, means acting and exerting pressure on the other side of the piston and thereby maintaining under pressure the fuel in the cylinder, a valve which retains the fuel in the cylinder after it has been delivered thereto, a valve controlling the flow of fuel from the said cylindrical chamber into the engine cylinder, means for actuating this fuel valve and thereby permitting the priming charge to flow to the engine cylinder, a pair of switch contacts in the said electric circuit with means for closing this switch when the said fuel valve is actuated and the fuel flow to the engine begins; and a second pair of switch contacts in the said electric circuit with means for closing this switch as the said piston in moving nears the end of its fuel delivery stroke, the closing of this second switch completing the electric circuit and causing the starter to function while the priming fuel is still entering the engine cylinder as set forth.
